UNITED STATES PATENT OFFICE

FRANK D. CHAPMAN, OF BERLIN, WISCONSIN

PEA-GRADING MACHINE

Application filed October 17, 1929. Serial No. 400,246.

This invention relates to improvements in pea grading machines.

It is to the advantage of the canner in grading peas to separate the peas into different sizes or grades as the smaller sizes are sold for higher prices than the larger sizes and the prices decrease as the peas increase in size. It is customary in grading peas to pass them over screens having different sized openings, starting with the smaller size openings and gradually increasing in size to the larger. Due to the large quantity of peas fed to the first grading screen many of the smaller sized peas are carried beyond the screen through the perforations of which they are adapted to pass, thus causing a loss to the canner.

It is one of the objects of the present invention to overcome this objectionable feature and provide a pea grading machine in which the first screen of the machine will separate the smaller size food units from the larger and then independently grade the smaller size units simultaneously with the remaining grading and grading of the larger size food units.

A further object of the invention is to provide a pea grading machine in which a portion of the divided load is regraded in passing through the machine.

A further object of the invention is to provide a pea grading machine in which the different grades or sizes are separated and discharged from different portions of the machine.

A further object of the invention is to provide a pea grading machine in which the screen units are all of the same length and diameter to permit rearrangement with relation to each other and various combinations of screen perforation sizes.

A further object of the invention is to provide a pea grading machine which is of simple construction and efficient in operation and is well adapted for the purposes described.

With the above and other objects in view the invention consists of the pea grading machine and its parts and combinations as set forth in the claims, and all equivalents thereof.

In the accompanying drawings in which the same reference characters indicate the same parts in all of the views:

Fig. 1 is a side view, parts in section, of the improved pea grading machine;

Fig. 2 is a front end view thereof; and

Fig. 3 is a transverse sectional view thereof taken on line 3—3 of Fig. 1.

Referring to the drawings the numeral 8 indicates the main frame which is of rectangular form in cross section. The upper portion 9 of the frame inclines downwardly rearwardly and supplemental frame members 10 incline downwardly in the same direction. Said last mentioned frame members are located intermediate the height of the frame.

Four upper shafts 11 are journaled on the upper portion of the frame and incline downwardly, rearwardly in the same plane as the frame parts and have fast thereon in equidistantly spaced relation supporting rollers 12. The inner rollers are grooved while the outer end rollers are plain or ungrooved.

A line of open ended drums 13, 14, 15, 16, 17, 18 and 19 in endwise abutting relation are positioned between each pair of upper shafts 11 and are provided with flanged annular end portions 18'. The drums are all of the same length and the end flanges of adjacent drums abut each other and extend in pairs into the grooves of the rollers 12 while the outer end flanges of the opposite end drums extend on the outer sides of the outer rollers 12. The rollers of each pair of shafts are closer together than the diameter of the annular flanged ends so that the lines of drums are supported on said rollers in an inclined position.

Other pairs of shafts 11' journaled in spaced relation on the supplemental frame 10 and extending longitudinally with relation to the frame and at a downward, rearward inclination, have rollers 20 mounted fast thereon. Supplemental drums 14', 15', and 16' having annular end flanged portions 23 are supported on the rollers 20 and abut each other in endwise relation in the same manner as the drums thereabove.

The body portions 24 of all of the drums between the annular end parts are formed of

perforated metal and the diameters of the perforations of the upper drums increase 1/32 of an inch in size from the second drum from the front or inlet to the rear of the machine along each line of drums, the first of said mentioned line of drums preferably having perforations 9/32 of an inch in diameter and the rear upper drum 19 having perforations of 14/32 of an inch in diameter. 5 Drum 14 having the smaller size openings will regrade and separate No. 1 grade peas from the larger sizes, drum 15 the No. 2 grade, drum 16 the No. 3 grade, drum 17 the No. 4 grade, drum 18 the No. 5 grade, and 10 drum 19 the No. 6 grade from the No. 7 which will be discharged from the rear end of the drum 19. The upper front drums 13, which may be termed the load splitting or dividing drums, are formed with perforations 12/32 of 15 an inch in diameter to permit the greater part of the Nos. 1, 2, 3 and 4 peas to be discharged therethrough and into the drums 14' below to divide the load.

One shaft of each pair of upper shafts 11 20 is rotated by a bevel gear connection 25 with an upper transverse driving shaft 26 having a belt wheel 27 mounted thereon, and one of the lower shafts 19 of each pair has a sprocket chain and wheel driving connection 28 with 25 the upper shafts 11 and is driven thereby. Said lower shafts are connected together in pairs by sprocket chain and wheel connections 28'.

Hoppers 29 positioned in front of the forward ends of the drums 13 feed peas or other food particles into said drums 13 and the downward rearward inclination and the rotation of the drums cause the peas to travel through the drums and be separated by dropping through the perforations which vary in size in the upper lines of drums until finally the No. 7 or largest size peas are discharged from the rear ends of the drums 19 and into the discharge spouts 30 located at said drum 45 ends.

Hoppers 31 partly surrounding the lower portions of the dividing drums 13 have discharge spouts 32 which extend downwardly and into the front ends of the supplemental 50 drums 14' to direct the mixed Nos. 1, 2, 3 and 4 peas divided from the mass in the drums 13 into said supplemental drums 14' and thus relieve the drums 14, 15 and 16 from portions of the load and thereby prevent possible injury to the smaller and more tender peas due to weight of a large mass, while at the same time expediting the separation of the peas. The lower drum 14' is formed with 9/32 diameter perforations to separate No. 1 55 grade peas, drum 15' has 10/32 perforations to separate No. 2 grade peas, and drum 16' has 11/32 perforations to separate No. 3 grade from the No. 4 grade peas as indicated in Fig. 1. The lower drums are preferably 60 respectively positioned below the upper 65

drums with correspondingly sized perforations so that the peas passing from the upper regrading drums can flow into the lower hoppers for corresponding grade sizes.

Hoppers 33 partly surrounding the lower portions of the drums 14' have discharge openings 34 therein through which No. 1 peas screened through the drums 14' are discharged. Hoppers 35 partly surround the lower portions of the drums 15' and have discharge openings 36 for the No. 2 peas screened through the drums 15'. Hoppers 37 extending around the lower portions of drums 16' have discharge openings 38 through which No. 3 peas from the drums 16' pass. The No. 4 peas from the drums 16' pass through said drums and are discharged therefrom through spouts 38.

The upper drums 14, 15 and 16 respectively have hoppers 39, 40 and 41 and spouts 42, 43 and 44 which extend downwardly between the lower drums and are connected respectively to the hoppers 33, 35 and 37 directly beneath which receive the same grade peas as clearly indicated in Fig. 3. The remaining upper drums 17, 18 and 19 respectively have hoppers 45, 46 and 47 and spouts 48, 49 and 50 for receiving the Nos. 4, 5 and 6 grade peas which are screened through the respective drums mentioned.

The spouts 38 from the drums 16' are connected to the spouts 48. Rollers 51 and 52 bearing against the upper portions of the drums serve to maintain the drums in position on the rollers 12 and 20.

As the drums are all of the same length and diameter except drum 13 they are easily interchangeable to provide various combinations of sizes or grades.

While the greater number of the Nos. 1, 2, 3 and 4 grade peas will pass through the perforations of the dividing drum 13, a few will not and these will pass longitudinally through the drum and into the next succeeding drums 14, 15 and 16 to be further regraded, so that when the peas reach the No. 5 screens all of the Nos. 1, 2, 3 and 4 will have been screened from the mass flowing through the drums.

It is to be understood that while the machine shown is of the double type, one longitudinal half section may be used, or any combination of or number of drums may be used without departing from the spirit and scope of the invention. It will also be understood that while the machine has been shown and described as a machine for grading peas, the diameter of the drum perforations and position of the drums may be changed to grade other food products as desired.

From the foregoing description it will be seen that the first drums divide the loads received and a predetermined proportion of each load is separated and diverted to a line of grading drums positioned below the first mentioned drums, thus relieving the upper

drums of grading all of the load, and furthermore providing a more complete separation of the smaller and more valuable peas from the larger.

5. What I claim as my invention is:

1. A food unit grading machine, comprising two lines of food unit size grading screens, and a food unit dividing screen positioned to receive a stream of food units and to divide the stream into two parts, one of the parts which passes through the dividing screen containing substantially all of the larger size units which are directed into one of the lines of screens for regrading to remove any remaining smaller size units from the larger size units and for grade size separation of the larger size units, the other part of the stream which passes through the perforations of the dividing screen and containing the smaller size units being directed into the other line of drums for grade size separation.
2. A food unit grading machine, comprising lines of rotary screen drums, one line being positioned above the other and the perforations of the screens of the front drums being of smaller diameter than the perforations of the screens of the next succeeding drums, hoppers for receiving units discharged through the screens of said drums, a load dividing rotary screen drum positioned to discharge unscreened food units of the larger size into the first of the upper line of drums for regrading to remove any remaining smaller size units from the larger and for grade size separation of the larger units, and a hopper adjacent the load dividing drum for directing the smaller size units screened through the dividing drum screen into the lower line of drums for further grading.
3. A food unit grading machine, comprising a frame, a line of downwardly inclined rotary screen drums journaled thereon in endwise relation, another line of lower downwardly inclined rotary screen drums journaled on the frame in endwise relation, the perforations of each succeeding drum being of greater diameter than those of the preceding drums, a load dividing screen drum positioned adjacent the upper front drum and through which the largest size food units pass before entering the upper line of drums, the perforations of said load dividing drum being larger than the perforations of the next succeeding drum for separating the smaller size units from the larger, means for feeding food units into the dividing drum, and means for receiving the divided smaller size food units screened through the dividing drum and directing them into the line of lower drums to be further divided.
4. A food unit grading machine, comprising a frame, a line of downwardly inclined rotary screen drums journaled thereon in endwise relation, another line of lower downwardly inclined rotary screen drums journaled on the frame in endwise relation, the perforations of each succeeding drum being of greater diameter than the preceding drums, a load dividing screen drum positioned adjacent the upper front drum and through which the largest size food units pass before entering the upper line of drums, the perforations of said load dividing drum being larger than the perforations of the next succeeding drum for separating the smaller size units from the larger, a hopper for feeding food units into the dividing drums, some of the upper drums regrading the units to remove any remaining smaller size units from the larger, and a hopper extending around the lower portion of the dividing drum and having a spout extending into one of the line of drums below to direct the smaller size units therein for further grade separation.
5. A food unit grading machine, comprising a frame, a line of downwardly inclined rotary screen drums journaled thereon in endwise relation and having screen perforations which increase in size from the front drum towards the rear drum, other lower downwardly inclined rotary screen drums journaled on the frame, a load dividing screen drum journaled on the frame in front of and in axial alinement with the upper drums and having screen perforations of larger size than the perforations of the next adjacent upper screen for separating the smaller size units from the larger, means for feeding food units into the dividing drum, some of the upper drums regrading the units to remove any remaining smaller size units from the larger, and a hopper below the load dividing drum for directing the smaller size units divided by said load dividing drum into the first lower drum for grade separation.
6. A food unit grading machine, comprising a frame, a line of downwardly inclined rotary screen drums journaled thereon in endwise relation, another line of lower downwardly inclined rotary screen drums journaled on the frame in endwise relation, the perforations of each succeeding drum being of greater diameter than the preceding drums, a load dividing screen drum positioned adjacent the upper front drum and through which the larger size food units pass before entering the upper line of drums, the perforations of said load dividing drum being larger than the perforations of the next succeeding drum for separating the smaller size units from the larger, a hopper for feeding food units into the dividing drums, some of the upper drums regrading the units to remove any remaining smaller size units from the larger, and a hopper extending around the lower portion of the dividing drum and having a spout extending into one of the line of drums below to direct the smaller size units therein for further grade separation.
7. A food unit grading machine, comprising a frame, a line of downwardly inclined

5 rotary screen drums journaled thereon and arranged for food units to pass from one to the other, another line of lower downwardly inclined rotary screen drums journaled on the frame and arranged for food units to pass from one to the other, the perforations of each succeeding drum being of greater diameter than the preceding drums, a load dividing rotary screen drum positioned adjacent the 10 upper front drum and through which the larger size food units pass before entering the upper line of drums, the perforations of said load dividing drum corresponding in size to the perforations of one of the intermediate drums to divide the smaller size units from the larger in passing through the drum, a 15 hopper for feeding food units into the dividing drum, some of the upper drums regrading the units to remove any remaining smaller size units from the larger, a hopper extending around the lower portion of the dividing drum and having a spout extending into the first of the line of drums below for receiving the smaller size food units, and hoppers for 20 the other drums for receiving the food units screened therethrough

8. A food unit grading machine, comprising two lines of rotary downwardly inclined food unit size grading screen drums, a rotary 30 downwardly inclined food unit dividing screen drum positioned to receive a stream of food units and to divide substantially all of the smaller size units from the larger, the larger size units which pass through the dividing drum being directed into one of the lines of drums for regrading to remove any remaining smaller size units from the larger and for grade size separation of the larger size units, the smaller size units which pass 35 through the perforations of the dividing drum screen being directed into the other line of drums for grade size separation to relieve the first line of drums of a portion of the load, and hoppers for the drums of the different lines for receiving the separated units.

9. A food unit grading machine, comprising an upper and a lower line of rotary downwardly inclined food unit size grading screen drums, an upper rotary downwardly inclined food unit dividing screen drum positioned to receive a stream of food units and to divide substantially all of the smaller units from the larger, the larger size units which pass through the dividing drum being directed into the upper line of drums for regrading to remove any remaining smaller size units from the larger and for grade size separation of the larger units, the smaller size units which pass through the perforations of the dividing drum screen being directed into the lower line of drums for grade size separation to relieve the upper line of drums of a portion of the load, and hoppers for the drums of the upper and lower lines 65 for receiving the separated units.

10. A food unit grading machine, comprising two lines of food unit grading screens, and a food unit dividing screen positioned to receive a stream of food units and to divide the stream into two parts, one of the parts containing substantially all of the larger size units and being directed into one of the lines of streams for grade size separation, and the other part containing all of the smaller size units which passed through the perforations of the dividing screen and being directed into the other line of drums for grade size separation, some of the drums of the line of drums for the larger size units also regrading the units to separate any remaining smaller size units therefrom.

11. A food unit regrading machine, comprising two lines of food unit size grading screens, a screen for dividing food units of a plurality of grade sizes into two parts and directing the part having the larger size units into one of the lines of screens for regrading to remove any remaining smaller size units and further grade size separation, the other part having the smaller size units being directed into the other line of screens for further grade size separation, and hoppers for the screens, some of the hoppers for one of the line of screens directing their food units into some of the hoppers of the other line of screens.

12. A food unit grading machine, comprising two lines of food unit size grading screens, a food unit dividing screen positioned to receive a stream of food units and to divide the stream in two parts, one of the parts which passes through the dividing screen containing substantially all of the larger size units which are directed into one of the lines of screen for regrading to remove any remaining smaller size units from the larger size units and for grade size separation of the larger size units, the other part of the stream which passes through the perforations of the dividing screen and containing the smaller size units being directed into the other line of drums for grade size separation, and means for combining the food units of like sizes from both parts of the stream of food units.

13. A food unit grading machine, comprising two lines of food unit size grading screens, a food unit dividing screen positioned to receive a stream of food units and to divide the stream in two parts, one of the parts which passes through the dividing screen containing substantially all of the larger size units which are directed into one of the lines of screen for regrading to remove any remaining smaller size units from the larger size units and for grade size separation of the larger size units, the other part of the stream which passes through the perforations of the dividing screen and containing

the smaller size units being directed into the other line of drums for grade size separation, and means for combining the food units of like sizes from both parts of the stream of food units into one volume by gravity.

5 In testimony whereof, I affix my signature.
